Primary Examiner — Rhea Shields*(74) Attorney, Agent, or Firm* — Quickpatents, LLC;
Kevin Prince(57) **CLAIM**

The ornamental design for a ball container, as shown and described.

DESCRIPTION

FIG. 1 is an exploded top perspective view of a ball container, showing my new design;
FIG. 2 is an exploded bottom perspective view thereof;
FIG. 3 is a front elevational view thereof, the rear elevational view being a mirror image thereof;
FIG. 4 is a left-side elevational view thereof, the right-side elevational view being a mirror image thereof;
FIG. 5 is a top plan view thereof;
FIG. 6 is a bottom plan view thereof;
FIG. 7 is a cross-sectional view thereof, taken along line 7--7 of FIG. 3; and,
FIG. 8 is a cross-sectional view thereof, taken along line 8--8- of FIG. 4.
The broken lines showing balls in FIGS. 1 and 2 depict environmental matter and form no part of the claimed design.
